UNITED STATES PATENT OFFICE.

LLEWELLYN GUDGELL, OF GALESBURG, ILLINOIS.

TRACK-LAYING MACHINE.

1,045,397.

Specification of Letters Patent. Patented Nov. 26, 1912.

Application filed August 18, 1911. Serial No. 644,876.

To all whom it may concern:

Be it known that I, LLEWELLYN GUDGELL, a citizen of the United States, residing at Galesburg, in the county of Knox and State 5 of Illinois, have invented a new and useful Track-Laying Machine, of which the following is a specification.

The invention relates generally to means for handling, laying and heeling railway 10 rails in positions on the ties. It will be manifest, as the nature of the invention is further disclosed and better understood, that the device may be used with equally facile and effective results in removing the rails 15 from the ties and placing them alongside thereof.

The invention relates more specifically to that type of machine which is adapted to run along or travel on rails which it has 20 itself laid, and to pick up other rails which have been thrown at the side of the track or road bed, and which machines include rail-carrying means adapted to be swung on a pivot into proper position to deposit the 25 rails for laying, gaging, heeling, shimming and spiking by the track men.

A principal object is to generally improve the construction and to vastly increase the capacity, utility, speed and efficiency of 30 devices of this character. In this connection it is a further object to save the greater part of the expense incident to the heretofore existing machines of this character, by accomplishing a much greater amount of 35 work with a less number of men.

Another object is to provide novel pivotal means for the boom or crane, the frame, and parts connected thereto.

It is an object to provide a machine comprising but a single truck and a single frame and boom.

The invention further contemplates a machine which will lay the rail of either side of the track with equal facility without 45 moving the truck or carriage and without the agency of a second or subsidiary truck or carriage which necessitates a supplemental track carried by the supporting carriage.

50 A still further object is to provide simple means for separating the working parts from the supporting truck or car; and in this connection to provide attached means for supporting the former after they have 55 been disassembled.

It is an object to provide novel means on

which the rear portion of the frame may travel in the act of swinging from or to either side.

I shall not endeavor to encumber this 60 specification and the accompanying drawings with descriptions and illustrations of elements or of modifications which are neither essential to nor form any part of the invention herein claimed. In fact, it will be 65 apparent without such that numerous changes may be made in the details of construction and by modifications involving merely mechanical skill, without departing from the spirit and scope of the invention, 70 which consists not only in such features as are specifically pointed out in the claims, but also in combinations of elements and the arrangement and disposition of the parts for co-action, as will also be pointed out in said 75 claims.

In the accompanying drawings which illustrate a preferred embodiment of the invention: Figure 1 is a top plan; Fig. 2, a side elevation; Fig. 3, a rear elevation; Fig. 4, a front elevation; Fig. 5, a top-plan detail, taken in the line 5—5 in Fig. 4; Fig. 6, a transverse sectional detail in the line 6—6 in Fig. 4; and Fig. 7, an enlarged detail perspective.

Coming now to a detail description of said drawing and referring thereto by numerals of reference, the same one of each is applied to the same part in each figure, 2, 2 represent the side frame bars; 3, 3, the end frame 80 bars; 4, 4, intermediate frame bars; 5, 5, stays; 6, 6, diagonal frame bars; 8, 8, axles; 9, 9, bearings therefor and 10, wheels mounted on said bearings. Excepting that the platform is absent and that this car is 85 longer, these parts are identical with those of an ordinary railway push car or truck and need not be further herein described.

11 designates a platform for a roller-box 14 comprising concentric plates or ribs 12 100 provided with bearings for the gudgeons of a nest of rollers 13 or other anti-friction means, said ribs being united at their ends by plates 15.

16 is an arciform bearing-box comprising 105 duplicate top and bottom pieces 17 and 18 respectively, and ends 23. The bottom 18 is adapted to traverse the rollers 13 in swinging the boom and connected parts as will presently appear.

19 is a triangular platform comprising 110 joists 20 fixed at their apex to the boom

hereinafter described, and is provided with a part floor 21. The joists pass through and are fixed to the box 16. 22 is a hand-board or brace. Fixed to and on plates 24 by rods 25 and lag screws 26 which are threaded into the platform 19 is a windlass 27 comprising standards 28, cross rods 27^a, bearings 29, crank-shaft 36 mounted therein, a driving pinion 30 fixed on said shaft, second bearings 31, a journal 32 fixed thereon, a reel 33 fixed on said journal, and a cog wheel 34 also fixed thereon and in mesh with said pinion. A ratchet 35 fixed on the crank-shaft and a pawl 37 pivoted on one of the standards 28 are adapted to lock said reel when required.

Reference is to be now had particularly to Figs. 2, 4, 5, and 6, 39 designates a plate-like truss fixed at its ends by bolts 40 and nuts 41 (Fig. 2) to a tie-plate 42 resting beneath the frame-bars 2, and is provided with a centrally disposed aperture 43, Fig. 6. 44 is a ball-carrying plate provided with a race 46 for a plurality of balls 45 and with a centrally disposed aperture, and is fixed to the truss 39 by lag screws 47 which are threaded also into the longitudinal bars 5. 48 is a bearing-plate provided with a central aperture for the reception of the shank of a pivot bolt 49, the head of which rests in a recess in the boom, and the shank of which engages a nut 50 adapted to be threaded up against the truss 39. The plate 48 is adapted to turn on the balls 45 in an evident manner. 51 is a boom or crane-arm, seated in a bracket comprising L-shaped members 52 which are fixed to the plate 48 by bolts 53; as shown at Fig. 4. The bolt 49 thus becomes a pivot on which the boom is swung. Fixed between the bracket arms 52, by bolts 53, with its end resting on the boom, is a tension post or mast 54 apertured near its top for the reception of a sheave 55 mounted on a journal 56, and in a lower plane apertured for the reception of a sheave 57 mounted on a journal 59. One end of a cable 60 which traverses the sheave 55 is fixed to the windlass reel and its other end carries rail tongs 61. A truss rod 62 which rests on the sheave 57 is fixed at its forward end to the boom and at its rear end to the platform 19. 63 is a turn-buckle. 64 are brace-blocks on the faces of the bracket arms 52. 65 is a step; 66 a hand rail; 67, counterbalance rails; 69, railway ties; 70, the track rails; 71, fish-plates; and 72, a rail grasped by the tongs 61.

In order that confusion might not result I have in some of the figures omitted the horses 74 and other parts elsewhere shown and herein described; and in order to more clearly illustrate certain features which are indistinctly shown in the principal figures, have shown them enlarged at Figs. 5 and 6.

In operation: assume loose rails to have been deposited alongside the ties and the truck to be standing on a section of laid track. The two men usually employed in rear of the machine will grasp said rear end and swing the parts supported on the bearings to bring the forward end of the boom into such position that the tongs may grasp the rail which it is desired to lay. This having been done, the windlass men will wind the cable upon the reel in an evident manner to thereby elevate the rail. The reel may then be locked by the pawl and ratchet, whereupon the boom may be swung on its pivot, the frame 16 rolling over the rollers 13 and relieving the rear portion of the boom from friction. It will be evident that when a heavy rail is being positioned there will be little or no friction or weight on said rollers. The rail is guided by one or even two operators, and if it is not at first brought to the proper position the truck may be run back or forth as may be necessary to effect proper placement. A shim may then be placed between said rail and the adjacent laid one and said rails heeled. Its companion having been similarly handled and positioned, the car may then be run forwardly on the rails thus laid, to pick up, transport and position another rail in like manner. It will not be necessary to at this time gage the rails thus laid, nor to provide them with fish plates. In relaying, the old spikes are but partly withdrawn, and the new rail may be slid up under the heads thereof in an evident manner, whereby gaging is saved. The application of the fish plates, as also the spiking, is done by the track men following in rear of the machine.

The counterbalance weights 67 are selectively employed when rails of various weights are being laid, one or more of the former being dispensed with when light rails are being handled. When the boom is swung to either side to grasp a rail, these weights 67 normally cause friction on the rollers 13. This is counteracted by one of the operators stepping on the step 65. The hand rail may be employed, if desired, in swinging the boom, which swings as freely to one side as to the other.

While it would be difficult to raise the apparatus from the track in its entirety, it is easily done by the workmen when the pivoted parts are disengaged from the car and parts permanently secured thereto, which include the ball and the roller bearings and the boom-bracket. In order to effect the disconnection it is necessary only to remove the nut 50 from the bolt 49, whereupon the boom and all parts supported thereby and attached thereto may be raised until the boom passes upwardly to such an extent that it will clear the tops of the bracket arms 52, and then carried to the place of deposit. In

order that it may not be necessary to stoop to deposit upon the ground the parts thus lifted, or to raise them from the ground when the device is again to be operated, (both of which would require extra help,) I have provided horses or like supports 74, one hinged at 75 to and beneath the boom and the other to and beneath the platform 16. They may be secured in inoperative positions and entirely out of the way by hooks 76 and eyes 77. In order that the boom and connected parts may not be swung to too great an extent I have provided a bent rod 78 fixed to the car, rod or chain 79 slidable 15 theréon, and a hook 80 secured to the boom whereby the parts may be disconnected, when the upper and lower structures are disconnected. After the upper structure has 20 been removed from the car the latter may be easily moved by the handle extensions of the framebars 2. The boom is strengthened and all tendency thereof to sag is obviated by the truss-rod 62 and turn-buckle 63.

Having thus set forth my invention I 25 claim as new the following, to-wit:

1. In combination with a car, a boom pivotally mounted approximately at its mid-length thereon, an anti-friction bearing supported on said car, means supported by and 30 adapted to traverse said bearing for supporting one end portion of said boom, a windlass supported above said boom and disposed near one end thereof, a cable operable by said windlass and extending to the 35 distant end of said boom, and rail-tongs carried by the free end of said cable.
2. In combination with a car, a boom pivotally mounted approximately at its mid-length thereon, substantially parallel with 40 the floor thereof, and adapted to reciprocate but not to rotate, an anti-friction bearing supported on said car, means supported by and adapted to traverse said bearing for supporting one end portion of said boom, 45 a windlass supported above said boom and disposed near one end thereof, a cable operable by said windlass and extending to the distant end of said boom, and rail tongs carried by the free end of said cable.
3. In combination with a car, a boom pivotally mounted approximately at its mid-length thereon and substantially parallel 50 with the floor thereof, an archiform bearing supported on said car, near one end thereof,

means supported by and adapted to traverse 55 said bearing for supporting one end portion of said boom, a windlass supported above said boom and disposed near one end thereof, a cable operable by said windlass and extending to the distant end of said boom, and 60 rail-tongs carried by the free end of said cable.

4. The combination with a car, of a bearing supported thereby, a continuous, horizontally arranged and horizontally swinging boom pivoted at its midlength and adapted to swing thereon, a roller bearing intermediate its pivotal point and one of its ends, a bearing-box embracing and fixed to said boom, its bottom adapted to traverse said 70 roller bearing, and means for elevating a track rail.

5. A track laying machine comprising a car, a ball-bearing supported thereby, a bearing-plate adapted to turn thereon, a 75 boom supported on said plate, a bearing-box secured to said boom intermediate its pivotal point and one of its ends, a tension post supported by said boom, a sheave mounted therein, a windlass supported above said 80 boom, a cable actuated by said windlass, and rail tongs carried by said cable.

6. A track laying machine comprising a car, a plate-like truss secured thereto, an apertured bearing fixed on said truss, an 85 apertured bearing-plate pivotally mounted on said bearing, a pivot-bolt disposed in the apertures in said bearing and plate, a boom supported on said bearing plate, a bearing concentric to said bolt, a bearing box fixed 90 to said boom and adapted to traverse said last recited bearing, a platform supported by said boom, a windlass supported thereon, a tension post adapted to turn with said boom, sheaves mounted therein, a cable traversing 95 one of said sheaves, one of its ends engaged with said windlass and its other with rail grasping means, and a tension rod traversing the other of said sheaves, one of its ends fixed to the platform and the other to the 100 boom aforesaid.

In witness whereof I hereto affix my signature this 14th day of August, 1911.

LLEWELLYN GUDGELL
